A. V. Troubridge

UNITED STATES PATENT OFFICE.

CHARLES T. BRADSHAW, OF COLLINGSWOOD, NEW JERSEY.

CROSSING-SIGNAL.

1,289,101.

Specification of Letters Patent. Patented Dec. 31, 1918.

Application filed July 12, 1916. Serial No. 103,802.

To all whom it may concern:

Be it known that I, CHARLES T. BRADSHAW, a citizen of the United States, residing at Collingswood, in the county of Camden and 5 State of New Jersey, have invented certain new and useful Improvements in Crossing-Signals, of which the following is a specification.

My invention relates to improvements in 10 railroad crossing signals. The object of my invention is to provide a signaling device of novel, simple and efficient construction and operation for signaling the approach of railroad trains to and their presence at crossings; and, with this object in view, my invention consists in the novel construction and 15 combinations of parts hereinafter fully described and particularly claimed.

In the accompanying drawings illustrating 20 my invention:

Figure 1 is a face view of my improved crossing signal.

Fig. 2 is a side view thereof.

Fig. 3 is a diagrammatic view, showing 25 the electrical connections of the actuating devices.

Fig. 4 is a vertical section through the signaling device, on line 4—4 of Fig. 2.

Fig. 5 is a vertical section through the 30 signaling device, on line 5—5 of Fig. 4.

Referring to the drawings, 2 designates a post or standard which is provided with a suitable supporting base 3. Supported on the upper end of the post 2 is a casing 6 which may be of any shape and size for its 35 intended purpose. As herein illustrated, this casing comprises, generally, a base portion 7 which is secured to the top of the post 2, two spaced facing walls 8, a top wall 9 and side walls 10, hinged, at 11, to the top wall 9 and forming doors by means of which access may 40 be readily had to the interior of the casing for repairs, adjustments and other purposes. The doors 10 are secured in the closed position shown by suitable screws 12 carried by 45 the base 7 and extending through holes in the doors 10 and having removable heads 13 adapted to engage the doors 10 and hold them in the closed position. By removing 50 the heads 13, the doors 10 may be opened when desired.

Supported within the casing 6 is an electric or other suitable lamp 14 adapted to provide the light for the signal. The light 55 from this lamp 14 shines through openings 15 in the facing walls 8; and the openings

15 form a cross, as shown in Fig. 1, to indicate a railroad crossing, as is the common practice.

Within the casing 6 and adjacent and in 60 close proximity to the two facing walls 8 thereof are two disks 16 secured on two short shafts 17 which are aligned with each other and are fitted to turn in brackets 18 rising fixedly from the base portion 7 of the casing 6. The shafts 17 project inwardly from the brackets 18 and have fixed thereon collars 19 which are provided with upwardly-projecting arms 20. The upper ends of the arms 20 are clamped between and connected by a 70 pair of bars or plates 21 which are secured together by bolts 22. One collar 19 has a downwardly extending arm 23 which is provided on its lower end with a weight 24. The disks 16, shafts 17, arms 20, bars 21 and 75 weighted arm 23 constitute a swinging frame which is adapted to be oscillated by swinging the weighted arm 23 back and forth, thereby oscillating the disks 16. Each disk 16 is provided with two sets of openings corresponding with the openings 15 in the adjacent facing wall 8 and being adapted to be brought into registry therewith in alternate succession when the disks are oscillated. One set of openings in each disk 16 is 80 covered with panels of clear or white glass 25 and the other set of openings in each disk 16 is covered with panels of red glass 26. When the disks 16 are at rest, as shown in the drawings, the panels of clear or white 85 glass 25 are in registry with the openings 15, and, therefore, the signal normally shows a clear or white cross. When, however, the disks 16 are oscillated, the panels of red glass 26 and the panels of clear or white 90 glass 25 are brought into registry with the openings 15 in alternate succession, thereby 95 flashing a red light and a clear or white light through the openings 15 and showing a red cross and a clear or white cross in alternate succession. 100

The light from the lamp 14 also shines through openings 27 in the side walls or doors 10 of the casing 6; and within the casing and adjacent to and in close proximity to the openings 27 is a plate or member 28 which extends around the top and down the sides of the casing and conforms to the curvature thereof. This plate 28 is secured to and carried by arms 29 which 105 project from the bars 21, whereby when the bars 21 and disks 16 are oscillated, the plate 110

28 will be oscillated. Each side of the plate 28 has two openings therein corresponding with the opening 27 in the adjacent side wall 10 of the casing, and being adapted to be brought into registry therewith in alternate succession when the plate 28 is oscillated. One opening in each side of the plate 28 is covered with a panel of clear or white glass 39 and the other opening in each side of the plate is covered with a panel of red glass 30. The panels of clear or white glass 39 rest normally in registry with the opening 27; and when the plate 28 is oscillated, the panels of clear or white glass 39 and the panels of red glass 30 are brought into registry with the openings 27 in alternate succession, thereby flashing a clear or white light and a red light through the openings 27 in alternate succession.

20 One of the collars 19 is provided with a spring arm 31 which projects outwardly and downwardly therefrom. Adjacent to the spring arm 31, and normally in contact therewith, is the free end of an arm 32 which projects from the armature 35 of an electro-magnet 33 which is mounted on a bracket 34 rising from the base 7 of the casing. The armature 35 is pivoted on a pin 36 in the bracket 34 and the armature 35 with its arm 32 are held normally in the position shown, with the armature 35 out of contact with the magnet 33 and an adjustable stop screw 37 against a lug on the bracket 34, by the action of a suitable spring 38 encircling the pin 36 and having one end thereof engaged with the armature 35 and the other end thereof engaged with the bracket 34. When the electro-magnet 33 is energized, its armature 35 is drawn into contact therewith, causing the armature arm 32 to act upon the spring arm 31 and turn the shafts 17 and swing the weighted arm 23, thereby turning the disks 16 and bringing the red glass panels 26 into registry with the openings 15 in the facing walls 8. Just before the panels 26 register with the openings 15, the movement of the arm 32 is stopped by the engagement of the armature 35 with the poles of the electro-magnet 33 and the spring arm 31 moves out of contact with the arm 32, thereby breaking the electric circuit which energized the electro-magnet 33, as will be hereinafter explained, and permitting the spring 38 to return the arm 32 to the normal position shown, and permitting the weighted arm 24 to swing back to the normal position and thus return the disks 16 to the normal position with the clear or white panels 25 in registry with the openings 15.

25 Mounted above the casing 6 on the top wall 9 thereof is a bell or gong 40 adapted to be struck by the weighted ends or heads 41 on the upper ends of striking levers 42 which are fulcrumed, at 43, on brackets 44.

28 secured to the top wall 9 of the casing. The lower ends of the levers 42 have openings therein and they surround the upper ends of levers 45 which are fulcrumed, at 46, on the brackets 44. The upper ends of the levers 45 extend through openings 47 in the top wall 9 of the casing and rest normally against the outer walls of the openings, being held in this normal position by the action of springs 48 which extend between the gong supporting post 49 and the heads 41 on the levers 42. The lower ends of the levers 45 are adapted to be struck in alternate succession by spring arms 50 projecting from the bars 21 when the disks 16 are rocked back and forth; and each time an arm 50 strikes a lever 45, the upper end of the lever 45 is moved over against the inner wall of the opening 47 through which it extends, thereby throwing the lower end of its lever 42 inwardly and the upper end thereof outwardly against the action of its spring 48 and causing the head 41 to strike the gong 40. Thus the gong 40 will be struck at each end of the movement of the disks 16, during the oscillation thereof, to sound an audible alarm during the flashing of the light or the actuation of the visual alarm. The levers 45 not only serve as actuating devices for the gong levers 42 but they also serve as stops to limit the movement of the disks 16, as the panels 25 and 26 thereof alternately come into registry with the openings 16.

30 Referring particularly to Fig. 3, I shall now describe the means for supplying electric current to the electro-magnet 33 for operating the signal. 60, 61 designate two railroad tracks, which may be called northbound and southbound tracks, respectively. The track 60 has two parallel rail sections 62 which form a block and are insulated from the other sections of the track 60; and the track 61 has two parallel sections 63 which form a block and are insulated from other sections of the track 61, the blocks 62 and 63 being the portions of the track at the crossing which is protected by the signal. The track sections 62 at one end thereof are connected by a wire 64 which includes a track battery 65; and the track sections 62 at the other end thereof are connected by a wire 66 which includes a relay 67. The track sections 63 at one end thereof are connected by a wire 68 which includes a track battery 69; and the track sections 63 at the other end thereof are connected by a wire 70 which includes a relay 71; and the rail sections 62 and 63 thus form two normally closed circuits including the relays 67 and 71 which when short circuited by the presence of cars in the blocks 62 and 63 will drop their armatures 72 and 73, respectively. 74 designates the local battery for the signal cir-

cuit for supplying current to the electro-magnet 33, and leading from one side of the battery 74 is a wire 75 which is connected to the armatures 72 and 73 of the relays 67 5 and 71, respectively. Leading from the other side of the battery 74 to the collar 19 carrying the spring arm 31 is a wire 76. The arm 32 of the armature 35 is connected to the electro-magnet 33 by a wire 77; and 10 leading from the electro-magnet 33 is a wire 78 having two terminal or contact portions 79 and 80 adapted to make contact with the armatures 72 and 73 of the relays. When either of the armatures 72 or 73 is 15 in contact with the terminals 79 or 80, respectively, the normally open signal circuit is closed through wire 75, battery 74, wire 76, collar 19, arm 31, arm 32, wire 77, electro-magnet 33 and wire 78; and when a car 20 is present on the track sections 62 and 63 of one or both of the crossing blocks, one or both, as the case may be, of the relays 67 and 71 will be short circuited and caused to drop one or both of the relay armatures 25 72 and 73 and thus close the local or signal circuit which will remain closed at the relay or relays while a train is passing over one or both blocks. Immediately when the local or signal circuit is thus closed, the magnet 33 attracts the armature 35, causing the arm 32 to move the arm 31 and swing the weighted arm 23 until the arm 31 moves out of contact with the arm 32 and breaks the signal circuit, whereupon the arm 32 is 30 returned to the normal position shown by the action of the spring 38 and the weighted arm 23 swings back and moves the arm 31 back into contact with the arm 32, again closing the signal circuit and again causing 35 the arm 32 to move the arm 31 and swing the arm 23 for a succeeding operation. Each time the arm 23 is swung back and forth, white and red lights are flashed from 40 the openings 15 and 27 of the casing 6 and the bell or gong 40 is sounded, as previously explained; and this flashing of the light and ringing of the gong is continued while a train is in either or both of the blocks 62 or 63. When a train leaves one 45 block and no train is in the other block the signal circuit will be broken at the relays 67 and 71 and the moving parts of the signal will come to rest in the position shown in the drawings with the arm 31 in contact 50 with the arm 32 for a succeeding signaling operation.

The signal is set with the facing walls 8 of the casing at right angles to the road crossing the tracks 60 and 61 so that the 55 flashes of light from the openings 15 may be seen by persons approaching the tracks 60 and 61 from either direction, and so that the engineers of trains on the tracks 60 and 61 can see the light from the openings 27 and thus know whether the crossing signal

is or is not operating and report it if not operating.

From the construction and operation of my improved signal, as herein shown and described, it will be seen that while a train 70 or trains are in a block constituting the danger zone of the crossing, a visual signal flashing a red and a white light alternately, will indicate the danger, and that the sounding of the gong will provide an audible 75 signal, indicating the danger. It will also be seen that when no train is present within the block constituting the danger zone, the signal will show a white cross, merely indicating the presence of a railroad crossing. 80 During the day time when the lamp 14 is not burning, there will be no flashes of light from the opening 15, while the signal is being actuated, but the red and white glass 85 panels 26 and 25, respectively, will be alternately brought into registry with the opening 15 and thereby indicate the presence of a train within the danger zone of the crossing.

90

I claim:

1. In a signaling device, the combination of a support, a signal including an actuating frame movable from and automatically returnable to a normal position, an electro-magnet, a movable contact part normally in 95 contact with a part of said frame and adapted to be operated by said magnet when energized to move said frame from its normal position and out of contact with said contact part and to return to a normal position when said magnet is deenergized, and a normally open electric circuit including 100 said magnet and said contact part and said frame, whereby when said circuit is closed said frame will be moved from and automatically returned to its normal position in alternate succession to actuate said frame.

2. In a signaling device, the combination of a support, a frame movable from and automatically returnable to a normal position, 105 visible and audible signals actuated by said frame when moved, an electromagnet, a movable contact part normally in contact with a part of said frame and adapted to be operated by said magnet when energized to move said frame from its normal position and out of contact with said contact part and to return to a normal position when said magnet is deenergized, and a normally 110 open electric circuit including said magnet and said contact part and said frame, whereby when said circuit is closed said frame will be moved from and automatically returned to its normal position in alternate succession to actuate said frame.

3. In a signaling device, the combination of a support, a swinging frame pivoted on 115 said support and adapted to be swung from and to automatically return to a normal position, a signal actuated by said frame when 120

125

130

- 15 moved, an electromagnet, a movable contact part normally in contact with a part of said frame and adapted to be operated by said magnet when energized to move said frame from its normal position and out of contact with said contact part and to return to a normal position when said magnet is deenergized, and a normally open electric circuit including said magnet and said contact part 10 and said frame, whereby when said circuit is closed said frame will be moved from and automatically returned to its normal position in alternate succession to actuate said frame.
- 15 4. In a signaling device, the combination of a support, a signal including an actuating frame movable from and automatically returnable to a normal position, an electromagnet, a pivoted contact part normally in 20 contact with a part of said frame and adapted to be moved on its pivot by said magnet when energized to move said frame from its normal position and out of contact with said contact part and to return to a normal 25 position when said magnet is deenergized, and a normally open electric circuit including said magnet and said contact part and

said frame, whereby when said circuit is closed said frame will be moved from and automatically returned to its normal position in alternate succession to actuate said frame. 30

5. In a signaling device, the combination of a support, a swinging frame pivoted on said support and adapted to be swung from and to automatically return to a normal position, a signal actuated by said frame when moved, an electromagnet, a pivoted contact part normally in contact with a part of said frame and adapted to be moved on its pivot 40 by said magnet when energized to move said frame from its normal position and out of contact with said contact part and to return to a normal position when the magnet is deenergized, and a normally open electric circuit including said magnet and said contact part and said frame, whereby when said circuit is closed said frame will be moved from and automatically returned to its normal position in alternate succession to actuate said frame. 45

In testimony whereof I affix my signature hereto.

CHARLES T. BRADSHAW.
